UNITED STATES PATENT OFFICE.

CHARLES S. HOPKINS, OF ARLINGTON, NEW JERSEY, ASSIGNOR TO THE
ELECTRIC BOILER COMPANY, OF ROCHESTER, NEW YORK.

BOILER.

SPECIFICATION forming part of Letters Patent No. 519,285, dated May 1, 1894.

Application filed May 9, 1893. Serial No. 473,567. (No model.)

To all whom it may concern.

Be it known that I, CHARLES S. HOPKINS, a citizen of the United States, residing at Arlington, in the county of Hudson and State of New Jersey, have invented certain new and useful Improvements in Boilers; and I do hereby declare the following to be a full, clear, and exact description of the invention, such as will enable others skilled in the art to which it appertains to make and use the same.

My invention relates to a water tube boiler, its object being to produce a boiler for steam and hot water heating, or for making steam for power purposes, which can be cheaply manufactured, is durable in use, economical, absolutely safe and non-explosive, and is extremely easy to handle as it may be set up by any ordinary mechanic.

Heretofore water tube boilers have been built by arranging a group of vertical rows of pipes at the side of, or on both sides of a single chamber or header. I have found by actual experiment, that by reason of the extreme weight of the boiler when so many pipes were connected into one header necessitated the use of considerable force to move it, and the joints would invariably be strained. In my invention each vertical row of pipes has a separate stand pipe. Also, the pipes of the different rows are arranged in pairs located on opposite sides of the headers, the top pipe of a pair on one side of a header being opposite or in line with the bottom pipe of a pair on the other side, and the top pipe of the last named pair being opposite or in line with the bottom pipe of another pair on the other side, and so on. In this way I find that forty per cent. better results for hot water are gotten than with the old plan. This is owing to the fact that in the old plan the force of the currents exhaust themselves in a large part by striking against each other, whereas in mine there is a continuous circulation, and the steam and hottest water are allowed to ascend to the top with the slightest possible friction.

To accomplish these objects my invention consists in certain details of construction and combinations of parts to be hereinafter described and then particularly pointed out in the claims.

In the accompanying drawings: Figure 1 is a vertical section through my improved boiler, and its casing. Fig. 2 is a vertical section on line II—II, Fig. 1, looking toward the rear of the boiler. Fig. 3 is a vertical section on line III—III, Fig. 1, looking toward the front of the boiler. Fig. 4 is a vertical section on line IV—IV, Fig. 1. Figs. 5, 6 and 7 are transverse sections on lines V—V, VI—VI, and VII—VII, Figs. 1, and 4. Fig. 8 is a detail view of the smoke-pipe.

Referring now to said drawings, 1, indicates the casing of suitable material of my improved water-tube boiler, 2, the fire-box, 3, the grate, and 4 the ash-pit. The fire-box and ash-pit are provided with suitable doors, such as 5, 6 respectively. A partition wall 7 is located at the rear of the ash-pit 4, and supports the central portions of the boiler. Vertical conduits or castings 8 are supported on the partition wall 7, and are of the shape in cross-section as shown in Figs 5, 6 and 7, they being arranged closely together side by side, in such way as to form with the partition 7 a dividing wall between the front and rear portions of the boiler casing. These conduits or castings I designate "stand pipes" and while they constitute with the partition 7 a dividing wall forming a front combustion chamber 9, and a rear combustion chamber 10, they end short of the top of the casing so as to leave a space 11, through which the products of combustion pass from the chamber 9 into the chamber 10. Each stand 8 pipe is provided with internally screw-threaded bosses 12, having flaring counterbored extensions 12^a, and arranged in zigzag form, see Figs. 4 to 7. Radiating from the stand pipes 8 are circulating pipes 13, 13^a, 14, 14^a, which are screwed into the bosses 12. These pipes are connected in pairs, as shown, by return bends 15, and the zigzag arrangement of the bosses produces a staggered arrangement of the pipes, see Figs. 2 and 3.

Connected with the lower end of each stand pipe is an inlet pipe 16, which leads from the supply header 17 located outside the casing. Above each stand pipe is an eduction pipe 18, extending from front to rear of the casing and connected at its front end with a circulating pipe 14^b. The rear ends of the eduction pipes 18 and of the circulating pipes 13^b,

are connected by suitable couplings with the short pipes 18^a, which lead to the flow header 19, located outside the top of the casing 1. Each pipe 18 and stand pipe 8, are connected by short pipes 20, between which the products of combustion pass down into the chamber 10 and out through the smoke-pipe 21, located below the boiler. This smoke pipe 21 is provided with a cylindrical head 21^a, at its inner 10 end, which has a longitudinal mouth or slot 21^b, adapted to be opened and closed by a swinging damper 21^c, the curve of which is concentric with that of the head. The pivot 21^d, of the damper constitutes the axis of the head 21^a. The two series of paired circulating pipes 13, 13^a and 14, 14^a, of each stand pipe 8, are so arranged that there are some of the pipes 13, 13^a, behind the fire-box, they being more numerous than pipes 14, 14^a. 15

20 The stand pipes 8 provide a water-back to the firebox, (which latter is formed by leaving the lower front portions of the stand pipes plain,) and commencing the pipes 14, 14^a, some distance upon the stand pipes, so that said 25 pipes will be located entirely above the firebox. The pipes 13, 13^a, 14, 14^a, are also so arranged that the upper pipe 13 of each pair of pipes of the rear series excepting the lower pair, is located opposite and in line with the 30 lower pipe 14^a, of each pair of pipes of the front series, and the upper pipe 14 of each pair of pipes of the front series is located opposite and in line with the upper pipe 13^a, of the rear series, excepting the two lowermost 35 pipes 13, 13^a. This arrangement is, therefore, such as that the stated upper pipes of the rear series discharge into the stand pipes 8 opposite the lower pipes of the front series, and vice versa, so as to secure a continuous 40 circulation. The circulation throughout the boiler is as indicated by the arrows. Each central stand pipe 8, with its complement of pipes, forms one complete section. Any number of sections may be placed side by side 45 and connected with the supply or header 17, and flow header 19.

By varying the number of sections and the lengths of the pipes screwed into the stand pipes, a great many sizes of boilers may be 50 obtained, with only one size for each stand pipe. The flared counterbored extension 12^a, of the bosses 12 readily admit the ends of the pipes 13, 13^a, 14, 14^a, so that they may be 55 screwed into the bosses with ease and rapidity. The flame and products of combustion pass between the pipes and keep the water very hot, and to properly distribute the heat baffle plates 22, 23, 24 are let into the cas-

ing of the boiler, thus causing the products of combustion to take a course near the front 60 and back at the top, and farther inward at the bottom of the rear chamber 10.

When the boiler is used for steam heating I run drip pipes 25 from the short pipes 18^a, to the inlet pipes 16. 65

Having thus described my invention, what I claim as new therein, and desire to secure by Letters Patent, is—

1. The combination with the fire-box, of the series of stand-pipes conjunctively forming 70 a water-back for the fire-box, a front series of circulating pipes connected with the said series of stand-pipes and located above the fire-box, a rear series of circulating pipes also connected with said series of stand-pipes, lower 75 supply pipes connected to said stand-pipes and upper eduction pipes extending from front to rear of the casing and communicating with each stand pipe, and a smoke-pipe whereby the products of combustion are permitted to pass up through the spaces between the front circulating pipes over the series of stand-pipes, down through the space between the rear circulating pipes, and out through the smoke pipe, substantially as set forth. 80 85

2. The combination of the series of stand-pipes conjunctively forming a water-back for the fire-box, circulating pipes, some of which are located above the fire box and others at the rear, each stand pipe and its circulating 90 pipes forming a section, eduction pipes located above the stand-pipes, spaced pipes connecting the eduction pipes and series of stand pipes, and arranged to permit the passage of the products of combustion between them and 95 over the series of stand pipes, substantially as set forth.

3. In a water-tube boiler, a group of sections, each section being separate and distinct from the other, and stand-pipes provided with 100 circulating-pipes, said stand-pipes being arranged closely together and conjunctively forming a water-back for the firebox, and said circulating pipes being staggered and arranged in pairs so that the top pipes of the 105 pairs on one side of each stand pipe will be opposite the bottom pipes of the pairs on the opposite side thereof, substantially as set forth.

In testimony whereof I affix my signature in 110 presence of two witnesses.

CHARLES S. HOPKINS.
